UNITED STATES PATENT OFFICE.

BERNARD H. SKELLY, OF BRIDGEPORT, CONNECTICUT.

FORCE-FEED LUBRICATOR.

1,323,554.

Specification of Letters Patent.

Patented Dec. 2, 1919.

Application filed April 5, 1918. Serial No. 287,334.

To all whom it may concern:

Be it known that I, BERNARD H. SKELLY, a citizen of the United States, residing at the city of Bridgeport, in the county of 5 Fairfield and State of Connecticut, have invented certain new and useful Improvements in Force-Feed Lubricators; and I do declare the following to be a full, clear, and exact description of the invention, such 10 as will enable others skilled in the art to which it appertains to make and use the same.

My invention relates to force feed lubricators substantially like the lubricator 15 shown and described in my Patent No. 1,268,369, issued June 18, 1918 or in my pending application, Serial No. 262,432, filed November 14, 1918, and has for its object to provide for selective lubrication 20 or limited lubrication in instances where the lubricator pistons or plungers are actuated by a cam or by a plurality of cams that are rigid together and have the same axis of rotation.

25 In my prior constructions, selective lubrication was obtained only by employing separate series of plungers and actuating cams, and the cam or cams of each series had, of course, different axes of rotation. In my 30 present invention, either a single plunger or any number of plungers, in a series of plungers that are actuated by a single cam or by a plurality of cams having the same axis of rotation, may be so disposed that 35 either a limited lubrication will be had or no lubrication whatever.

In the accompanying drawing—

Figure 1 is a sectional elevation of a structure embodying my improvement, the 40 section being taken at the line 1—1 of Fig. 2—

Fig. 2 is a section at the line 2—2 of Fig. 1—

Fig. 3 a broken sectional elevation, similar to Fig. 1, but showing a plunger completely depressed and locked down, and

Fig. 4 a view similar to Fig. 3 but showing a plunger locked down when partly depressed so that such plunger will have a 50 short pumping stroke for limited lubrication.

Similar numerals of reference denote like parts in the several figures of the drawing.

A casing or reservoir 1 has a cover plate 55 2 by the removal of which access may be ob-

tained to the interior working mechanism of the lubricator.

A cylinder block 3 is contained within the casing and may be formed therewith or separately secured therein as desired, it 60 merely being necessary that there should be suitable communication between the oil in the reservoir and the inlet 4 of each pump cylinder 5.

The bottom of each cylinder is counter-bored to provide valve seats for the valves 6.

Laterally and outwardly from each cylinder leads an outlet port 7 adapted to receive a valved nipple (not shown) for connection with the mechanism to be lubricated. 70

A plunger 8 is vertically operable in each cylinder, and the plungers are normally held in elevated position by encircling coil springs 9 interposed between the 75 heads 10 of the plungers and the cylinder block.

Above the plungers is a cam shaft 12 whose ends are suitably journaled in the end walls of the reservoir, the shaft being 80 extended and provided with a suitable crank 13 for purposes of operation, but of course, a wrench hold on the shaft for attachment of a ratchet wrench can be employed instead of the crank. 85

A pair of cams 14 and 15 are carried on the shaft, said cams being longitudinally and eccentrically bored to receive the shaft, and are fixed thereon by the transverse key pins 16. The cams are relatively at an angle 90 of approximately 180°.

As shown in the drawing there are two sets of plungers 8 which are always held against their respective cams by the 95 springs 9.

The construction so far as described is the same as that forth in my pending application above noted, the object being to provide for a clear understanding of my present invention without any particular or 100 detail reference to said application.

Now, with sole regard to the present improvement, attention will be called to the manner in which limited or selective lubrication is effected. 105

17 is a ledge extending from the block 3 and overhanging the reservoir, and 18 are vertical rods whose lower extremities are fixed in any suitable manner to said ledge and whose upper ends are screw threaded. 110

19 are bridge plates which extend between said rods and the opposite plungers and loosely encircle the rods at one end and at the other end are secured to the plungers so as to always move in harmony therewith. As a convenient way of securing these plates to the plungers, I have shown the heads 10 separate from the plungers each head being provided with a separate threaded stem *a* which is driven within a threaded socket in the top of the plunger, with the plate 19 encircling the stem and confined between the top of the plunger and the head 10. 20 are sleeves around the rods 18 and 15 capable of free sliding movements, and, 21 are nuts driven on the upper ends of the rods and extending immediately above the tops of the sleeves 20.

When the plungers are depressed by the action of the cams the bridge plates 19 and the sleeves 20 will move downwardly, as shown at Figs. 1 and 2, and on the upward movements of the plungers these plates and sleeves will be carried upwardly as is shown at Fig. 2.

After a plunger has been depressed by a cam it may be securely locked in this depressed position by driving the nut down against the top of the sleeve as shown at Fig. 3, so that on repeated revolutions of the cam such plunger will remain stationary and therefore will effect no pumping of the lubricant whatever.

Should limited lubrication be desired the nut will be driven down against the top of the sleeve after the plunger has partially risen, and such plunger will then be held in this position and will be only actuated with a limited stroke during the succeeding movements of the cam.

This limited lubrication is illustrated more particularly at Fig. 4, the difference between the bridge plate in solid and dotted lines denoting the limited stroke of the plunger.

Of course, it will be readily understood that while I have illustrated in the drawing only two plungers beneath each cam element, as many of such plungers as may be desired may be actuated by each cam, each plunger having its corresponding rod,

bridge plate, sleeve and nut, and it will therefore be clear that any desired number of plungers may be selected either for non-lubrication or partial lubrication, and since 55 these plungers are all identified with the particular locations to be lubricated such selection may be intelligently made.

While I have illustrated my present invention in connection with the structure shown and described in my pending application above noted, it will be clear that this invention is equally applicable to a structure like that shown in my patent to which I have referred. 65

I claim—

1. In a force feed lubricator comprising spring retracted pumping plungers and means for depressing the same, means for locking a selective number of said plungers 70 in depressed position.

2. In a force feed lubricator, the combination of a series of spring retracted pumping plungers operable to deliver a lubricant through individual outlets and rotary cams 75 for depressing said plungers, of means identified with each plunger for locking selective plungers in depressed position.

3. A force feed lubricator comprising a reservoir, a cylinder block structure therein 80 having aligned cylinder bores provided with inlet and outlet ports, spring retracted plungers operable in the cylinders, rotary cams for depressing the plungers, a rigid vertical rod opposite each plunger and having a threaded upper end, a slideable bridge piece surrounding said rod and plunger and confined at its inner end between the head of the plunger and its spring, a slideable sleeve surrounding the rod and resting 85 upon said plate, and a nut driven on the upper end of said rod above said sleeve, whereby when the plunger is in depressed position said nut may be driven against the top of the sleeve to limit the stroke of said plunger.

In testimony whereof I affix my signature in presence of two witnesses.

BERNARD H. SKELLY.
